UNITED STATES PATENT OFFICE.

EDWARD A. LITTMANN, OF CUDAHY, WISCONSIN.

DESIGN FOR AN ICE-CREAM DISPENSER.

Application filed May 23, 1927. Serial No. 22,130. Term of patent 3½ years.

To all whom it may concern:

Be it known that I, EDWARD A. LITTMANN, a citizen of the United States, residing at 1015 Packard Avenue, Cudahy, in the county of Milwaukee, State of Wisconsin, have invented a new, original, and ornamental Design for Ice-Cream Dispensers, of which the following is a specification, reference being had to the accompanying drawing, forming part thereof.

Fig. 1 is a perspective view of the ice cream dispenser showing my new design.

Fig. 2 is an enlarged detailed view of the scoop shown in Fig. 1.

Fig. 3 is an enlarged detailed cross sectional view of the scoop shown in Fig. 1.

I claim:

The ornamental design for an ice cream dispenser substantially as shown and described.

In testimony whereof I affix my signature at 123 Wisconsin Avenue, Plankinton Building, Milwaukee, Wisconsin.

EDWARD A. LITTMANN.
